AMPLIFYING SYSTEM

Albert Preisman, Flushing, N. Y., assignor to
 Radio Corporation of America, a corporation
 of Delaware

Application December 31, 1940, Serial No. 372,462

2 Claims. (Cl. 179—171)

This invention relates to amplifying systems, and more particularly to amplifying systems having substantially no phase distortion over a wide frequency band.

In television systems wherein it is necessary to transmit an extremely wide band of frequencies and wherein phase distortion is a serious problem, it is necessary that the amplifiers employed be substantially free from phase distortion. It is well recognized that the phase relation between input and output circuits of various frequency components present in video signals must be maintained because any relative phase displacement between frequency components results in a serious loss in definition of the reproduced picture. In this connection, it is exceedingly important that the low frequency components have their initial phase relation free from any variation or deviation since the low frequency components represent background values. Any phase displacement between frequency components destroys the sharpness of detail inasmuch as the frequency components do not coincide in proper spacial relation with the background so that a distorted image is reproduced.

By properly choosing the constants of adjacent plate circuits and the grid circuit of an amplifier, it is possible to provide an amplifying system whose low frequency response is substantially free from phase distortion and there is also an increase in the over-all gain of the amplifier.

Furthermore, non-linear very low frequency phase shift usually causes variation in shading in the background of a scene, and also tilts the low-frequency blanking pedestals.

It has previously been proposed to provide an amplifying system with a plurality of stages having their plate circuit constants so chosen with respect to their grid circuit constants of the following stage that freedom from phase distortion has been obtained. In my Patent 2,243,121, issued May 27, 1941, I have taken into account the filter circuit of the power supply feeding the plate circuit of a triode tube, as well as the plate load impedance, and by selecting the grid coupling and the grid circuit of the following triode amplifier so that it is similar in its impedance characteristic to the combined plate load filter circuit. By making the two networks similar in their impedance characteristic, the phase angle of the energy components fed between the grid and cathode of the second thermionic amplifier is identical with the phase angle of the energy components impressed across the input of the first tube.

According to this invention, the input circuit of a constant current device such as a pentode tube is designed to have an impedance characteristic similar to the impedance of the output circuit of the previous constant current device.

The primary object of this invention is to provide a new and improved amplifying system which has substantially uniform amplitude and phase characteristics over a wide band of frequencies.

Another object of this invention is to provide an amplifying system in which the plate load filter circuit of one tube is made to have similar impedance characteristics to the grid coupling circuit network of the following tube.

Still another object of this invention is to provide an amplifying system including pentode tubes in which the plate load filter circuit of one tube is made to have similar impedance characteristics to the grid coupling circuit network of a following tube.

Other and incidental objects of the invention will be apparent to those skilled in the art from a reading of the following specification and an inspection of the accompanying drawing in which

Figure 1 is a circuit diagram showing one form of this invention, and

Figures 2, 3, 4 and 5 show equivalent circuit diagrams for the purpose of illustrating the development of the proper values of circuit elements to be used in accordance with this invention.

Referring now to Fig. 1, there is shown a signal input circuit whereby a signal including a plurality of frequency components is applied between the control electrode 1 and the cathode 3 of a tube 5 which may be of the pentode type. The output circuit of the tube 5 is connected to the anode 7 and includes a peaking coil 9 connected in series with a load resistance 11 which, in turn, is connected in series with a parallel circuit including a condenser 13 and a resistance 15. A grid coupling condenser 17 is shunted by a resistance 19 through which the signal is impressed upon the control electrode 21 of the tube 23. The input circuit to the tube 23 which is connected to the control electrode 21 includes a resistance 25 connected serially with a parallel circuit including a resistance 27 and a condenser 29. The output signal is supplied by the tube 23 through its anode 31. The operation and the selection of proper circuit elements may best be explained by reference to Figs. 2, 3, 4 and 5.

In Fig. 2 there is shown an equivalent circuit diagram of a typical pentode amplifying tube stage. Such a typical circuit, with the exception

of the high frequency peaking coil, is shown in Fig. 1. The portion shown in broken lines represents the grid coupling circuit of the succeeding stage.

As set forth in more detail in my Patent 2,243,121, issued May 27, 1941, the solid line portion of the circuit may be replaced by an equivalent circuit shown in Fig. 3. The transformation equations are:

$$\left. \begin{aligned} R_A &= \left(\frac{R_L}{R_p} \right) (R_L + R_s) \\ R_B &= (R_L + R_s) \\ C_A &= C_p \left(1 + \frac{R_L}{R_p} \right)^2 \end{aligned} \right\} \quad (1)$$

If R_B is regarded as made up of two resistors r_p and R_c in parallel, we obtain Fig. 4, which can then be re-transformed into Fig. 5 by the transformation formulas:

$$\left. \begin{aligned} R'_L &= \frac{R_A R_c}{R_A + R_c} \\ R'_p &= \frac{R_c^2}{R_A + R_c} \\ C'_p &= C_A \left[1 + \frac{R_A}{R_c} \right]^2 \end{aligned} \right\} \quad (2)$$

But Fig. 5 would be the equivalent constant current circuit for a triode having an internal current circuit for a triode having an internal plate resistance r_p , and a load made up of R'_L , R'_p , and C'_p as shown. In other words, Fig. 5 represents a triode feeding a plate load of the same form as the original pentode in Fig. 2 and exactly equivalent to it in performance.

The equivalent triode of Fig. 5 can now be used, and the formula necessary to determine the grid coupling circuit shown in Fig. 2 in broken lines is as follows:

$$\left. \begin{aligned} C_t &= C'_p \left[\frac{m+1+mK}{m(m+1)} \right] \\ R_{pt} &= R'_p \left[\frac{m(m+1)}{m+1+mK} \right] \\ C_b &= C'_p \left[\frac{m+1+mK}{m^2 K} \right] \\ R_b &= R'_p \left[\frac{m^2 K}{m+1+Km} \right] \end{aligned} \right\} \quad (3)$$

where

$$\frac{R'_L}{r_p} = K$$

and

$$R_t = m R'_L$$

It therefore follows that by transforming the pentode into some equivalent triode there has been obtained a circuit containing two elements C_b and R_b which can be used as a bias circuit for the grid.

Let R_B (Fig. 3) be broken up into two parallel resistors r_p and R_c in such manner that

$$\frac{R_c}{r_p} = q \quad (4)$$

Since

$$\frac{r_p R_c}{R_c + r_p} = R_B$$

and $R_B = R_L + R_F$, we obtain

$$r_p = \left(\frac{q+1}{q} \right) (R_L + R_F) \text{ and } R_t = (q+1)(R_L + R_F) \quad (5)$$

It will be noticed that R_L and R_F and C_F (Fig. 2) are predetermined for the actual pentode by high frequency and decoupling considerations, respectively.

It will be noticed from Equation 1 that

$$R_A = \left(\frac{R_L}{R_p} \right) (R_L + R_s) \quad (1)$$

so that, from Equation 2 there may be found 10 for Fig. 5:

$$\left. \begin{aligned} R'_L &= \frac{(q+1)R_L}{1 + q \left(\frac{R_F}{R_L + R_F} \right)} \\ C'_p &= C_p (q+1)^2 \left[\frac{q}{\left(1 + \frac{R_L}{R_F} \right)} + 1 \right]^2 \\ R'_p &= \frac{(q+1)^2 (R_L + R_s)}{R_L / R_p + (q+1)} \\ K &= \frac{R'_L}{r_p} = \frac{q R_L}{R_L + R_s (1+q)} \end{aligned} \right\} \quad (6)$$

Usually $(R_F + R_b)$ is fixed by the permissible value of resistance in the grid circuit, for example, R . Also, usually m is a large number compared to unity. Hence, in Equation 3 we have the approximate value

$$R_b \approx R'_p m \left(\frac{K}{K+1} \right) \quad (7)$$

From Equation 2 there may be obtained after some algebraic manipulation

$$(R_b + R_t) = R \approx m \left[R'_p \left(\frac{K}{K+1} \right) + R'_L \right] = m R_t (q+1)$$

or

$$m \approx \frac{R}{R_t (q+1)} \quad (8)$$

There is thus established that all factors which are necessary for determining C_t , R_{pt} , C_b and R_b in terms of R_L , R_F , and C_F , and q . The value of 45 q is quite arbitrary and may be chosen so as to make the grid circuit parameters take on any convenient values, although in all cases $R_b + R_t$ will not exceed R , the permissive value of grid circuit resistance.

50 The method of obtaining parameters C_b and R_b for a pentode tube depends solely upon the circuit equivalents given in Figs. 2 to 5 and upon Equations 1, 2 and 3. The method that follows Equation 3 is merely an attempt to show how C_b , 55 R_{pt} , C_b and R_b may be conveniently determined in terms of the original pentode tube parameters R_L , C_F , and R_F , and is not necessary to prove that the complete circuit configuration of Fig. 2 is possible for a pentode tube.

60 While several systems for carrying this invention into effect have been indicated and described, it will be apparent to one skilled in the art that this invention is by no means limited to the particular organizations shown and described, but 65 that many modifications may be made without departing from the scope of this invention as set forth in the appended claims.

I claim as my invention:

1. An amplifying system comprising a first 70 amplifier tube having an output load circuit comprising two series resistances with a condenser connected in parallel with one of the resistances, a second amplifier tube having an input circuit comprising two series resistances with a condenser connected in parallel with one of the re-

sistances, a coupling circuit between the output and input circuits comprising a condenser and a resistance connected in parallel therewith, the value of the one resistance and parallel condenser in said input circuit and the value of the condenser and parallel resistance in said coupling circuit being so chosen in accordance with the value of the one resistance and parallel condenser in said output circuit that the impedance characteristics of the input circuit will be similar to 10 the impedance characteristics of the output circuit.

2. An amplifying system comprising a first amplifier tube having an output load circuit including two series resistances with a condenser con- 15

nected in parallel with one of the resistances, a second amplifier tube having an input circuit including two series resistances with a condenser connected in parallel with one of the resistances, 5 a coupling circuit connected between the output and input circuits including a condenser and a resistance connected in parallel therewith, the values of the condensers and the parallel resistances in said input and coupling circuits being so chosen in accordance with the impedance of said output circuit that substantially uniform amplification and phase characteristics will be maintained over a wide band of frequencies.
